UNITED STATES PATENT OFFICE

168,426

COMBINED CONTAINER AND CHILDREN'S APPAREL DISPLAY

Nathan S. Siegel, Minneapolis, Minn.

Application September 11, 1952, Serial No. 21,409

Term of patent 14 years

(Cl. D80—5)

To all whom it may concern:

Be it known that I, Nathan S. Siegel, a citizen of the United States of America, residing at 5004 Newton Avenue, South, Minneapolis, county of Hennepin, State of Minnesota, have invented a new, original, and ornamental Design for Combined Container and Children's Apparel Display, of which the following is a specification, reference being made to the accompanying drawing, forming a part thereof, and in which:

Fig. 1 is a top plan view of a combined container and children's apparel display showing my new design.

Fig. 2 shows an edge view of my combined container and children's apparel display.

The dominant features of my design reside in the portions shown in full lines.

The rear of the display package is plain and unornamented.

I claim:

The ornamental design for a combined container and children's apparel display, substantially as shown and described.

NATHAN S. SIEGEL.
